CLAIM

We claim the ornamental design for a support plate and connector for a hook arm, for a universal connection of a wiper blade, as shown and described.

DESCRIPTION

FIG. 1 is a front view of a support plate and connector for an hook arm, for a universal connection of a wiper blade showing our new design;

FIG. 2 shows the connector of FIG. 1 in a bottom view;

FIG. 3 shows the connector of FIG. 1 in a right side view;

FIG. 4 shows the connector of FIG. 1 in a top view;

FIG. 5 shows the connector of FIG. 1 in a left side view;

FIG. 6 shows the connector of FIG. 1 in a rear view; and,

FIG. 7 shows the connector of FIG. 1 in a left side perspective view.
